UNITED STATES PATENT OFFICE.

EDMUND ZÖLLER, OF NEW YORK, N. Y.

BUTTON.

SPECIFICATION forming part of Letters Patent No. 365,894, dated July 5, 1887.

Application filed November 4, 1886. Serial No. 217,998. (No model.)

To all whom it may concern:

Be it known that I, EDMUND ZÖLLER, a citizen of the United States, residing at New York city, in the county and State of New York, 5 have invented new and useful Improvements in Buttons and Holders for Cuffs and other Articles, of which the following is a specification.

This invention relates to buttons and holders for cuffs, wristbands, and similar articles; and the invention consists in the features set forth in the following specification and claims and illustrated in the accompanying drawings, in which—

15 Figure 1 shows the device applied to a wristband and to a cuff. Fig. 2 is a section in the plane $x x$, Fig. 3. Fig. 3 is a plan view of the device. Fig. 4 is a side elevation of a modification. Fig. 5 is a side elevation of another modification.

20 Similar letters indicate corresponding parts. In the drawings, the letter A indicates a base or support formed of suitable material—such, for example, as one or more metal plates. 25 The plates may be flat, hollowed, or otherwise shaped, as may be useful or ornamental. In case two or more plates are employed, they are suitably fastened together by solder or other suitable means, so as to form the base A.

30 To the two opposite sides of the base A are connected swinging, pivoted, or hinged fastening devices composed of arms or buttons B, which can be swung on their pivotal attachment to bring them in line, or substantially so, with a vertical line taken centrally through the base A, Figs. 2, 4, and 5, or be swung laterally to place them at right angles, or substantially so, to said line.

35 The fastening devices may be composed of 40 swinging spring-arms B, pivoted to one side of the base A, and a swinging button or disk pivoted to a post, C, secured to the other side of the base, as in Fig. 4; or the base A may have oppositely-projecting posts C, to each of 45 which a swinging button or disk, B, is pivoted, as in Fig. 5. By this arrangement the face of the buttons B may be swung into a plane lying in the direction of the axes of the arms C, as seen in dotted lines in Fig. 5, so that

the buttons B can be readily passed through 50 such openings—as, for example, the button-holes of a stiffly-starched cuff.

In place of buttons B, the base A may be provided with swinging arms B, in the form of C-springs, pivoted or hinged to the opposite 55 sides of the base, as in Figs. 2 and 3. When it is desired to attach the device—for example, to a cuff—the arms or fastenings B B are swung away from the base A, whereby the arms B are caused to lie close together, as seen 60 in Figs. 2 and 3 in full lines, in which position they can be readily passed through a button-hole, after which the arms B are swung so as to lie against or close to the base A, as seen in dotted lines in Figs. 2 and 3, when they 65 clamp or secure the edges of the button-hole to the base A.

If desired, the base A may be provided on one side with spring arms or levers and on the other side with a fixed or a movable button. 70 Such arrangement with a movable button is seen in Fig. 4. The device is very useful—for example, in attaching cuffs to wristbands. One of the fastenings B can in this case be utilized to grasp the button-holes at 75 opposite edges of a wristband, thus closing the wristband about the wrist. The other fastening B can then be utilized to grasp two button-holes at opposite edges of a cuff, whereby the cuff is not only held or fastened to the 80 wristband, but the cuff is at the same time held closed about the wristband, so that the cuff sits smoothly about the wrist of the wearer and presents a slight appearance, as seen in Fig. 1. The free end of the cuff can have its 85 edges provided with a sleeve-button or other ornament, E.

What I claim as new, and desire to secure by Letters Patent, is—

1. A cuff and wristband holder consisting 90 of the base A, having a shank, C, at one side, carrying an arm, B, and provided at its opposite side with a swinging spring-impelled arm or arms, B, or their described equivalents, adapted to swing into a position substantially 95 parallel to and also at right angles to the side of the base, as and for the purposes set forth.

2. A cuff and wristband holder consisting

of the base A and the swinging spring-im-
pelled arms B, or their described equivalent,
pivoted, respectively, to the opposite sides of
the disk, to swing into positions substantially
5 parallel to and also at right angles to the sides
of the base, substantially as shown and de-
scribed.

In testimony whereof I have hereunto set my
hand and seal in the presence of two subscrib-
ing witnesses.
